UNITED STATES PATENT OFFICE.

EMILE N. TROTTIER, OF NORTH ADAMS, MASSACHUSETTS.

GAS-STOVE-VALVE LOCKING DEVICE.

Application filed April 7, 1927. Serial No. 181,819.

This invention relates to new and useful improvements in locking devices for gas stove valves and aims to provide a device of this character that is exceedingly improved over the device shown and described in my co-pending application, Serial No. 160,409, filed January 11, 1927.

To the attainment of this end there is provided easily operable means disposed adjacent the handle of the gas stove valve for releasing the valve so that it may be properly turned, said means being constructed complementary to other units of the device to normally maintain the valve in a predetermined set position, the locking unit per se being operable automatically to valve locking position.

In the drawings, wherein like reference characters designate like parts throughout the views:

Figure 1 is a side elevation of one of the control valves of a conventional gas stove disposed between the gas distributing pipe and a particular burner, said valve being equipped with my improved means for facilitating the locking of the valve.

Figure 2 is a top plan view thereof.

Figure 3 is a side elevation opposite to that disclosed in Figure 1.

Figure 4 is a vertical section taken through the burner attached nipple of the valve, and looking outwardly for disclosing my attachment in rear elevation.

Figure 5 is a horizontal section taken substantially upon the line 5-5 of Figure 1, and looking downwardly in the direction of the arrows.

Figure 6 is a detail fragmentary section through the locking unit of the attachment, and

Figure 7 is an elevation of the locking pin.

Figure 8 is a plan view of one of the valve body attachment members of the device.

Now having particular reference to the drawings, 5 designates the body of a conventional gas stove valve, the inlet nipple thereof being arranged within the usual manifold gas distributing pipe 6, the usual core of the valve being equipped at its upper end with a stem 7, to which is attached the inner ball like head of a conventional valve handle 8. Constructed for vertical disposition upon one side of the valve body 5 is a clamping plate 9, preferably of sheet metal,

the upper end thereof being formed with a horizontal substantially semi-circular segment 10, while the lower end thereof is of widened formation and provided with openings 11-11. This segment 10 is preferably formed integral with the plate 9, said plate and segment being preferably stamped from a strip of sheet metal, after which the segment is turned over at right angles as indicated more clearly in Figure 4, the stamped unit being clearly disclosed in Figure 8. The ends of the segment 10 are then turned downwardly to provide a pair of attaching ears 12-12 for a purpose hereinafter more fully described. Furthermore, this segment 10 is provided throughout substantially its entire length with spaced circular openings 13, the purpose of which will also be herein-after fully set forth.

For arrangement upon the opposed side of a valve body 5 is another clamping plate 14, the upper end thereof being considerably widened so as to provide ears 15-15 formed with openings to register with the openings in the ears 12-12 of the segment 10, so that the same may be interconnected by screws 16-16. Furthermore, the lower end of the plate 14 is also widened and provided at the ends of this widened portion with openings registering with the openings 11-11 in the first mentioned clamping plate 9, so that these plates may be further secured at their lower ends by elongated screws 17-17.

The invention further consists of a two plate clamp, designated generally by the reference character 18, the same consisting of a pair of clamp plates 19 and 20, that are shaped for disposition over the inner headed end of the valve stem handle 8, as clearly disclosed in Figures 1 and 3. The four corners of these plates are spaced from the handle and head and are secured together by set screws or the like 21. The rear edges of these plates 19 and 20 are formed directly above the segment 10, with a pair of curved jaws 19' and 20, respectively, that combine to form a sleeve that is threaded internally for receiving a threaded pin guide 22, the upper end of which is closed and provided with a knurled thumb nut 23. Slidable within this guide 22 is a short plunger 24, arranged upon the lower end of a vertically extending pin 25, that is slidable through an opening in the upper closed end of the guide, as clearly disclosed in Figure 6. The bottom of the plunger 24 is provided with

a central depending tit 26, for engagement in any predetermined one of the openings 13, in the plate segment 10. Surrounding the pin 25 within the guide 22 and back of the plunger 24 is an expansible coil spring 27, for normally forcing the plunger 24 downwardly so that the tit 26 will automatically engage within the openings 13 of the segment 10, when the plunger associated pin 25 is released against the action of the spring 27.

Loosely pivoted to the upper edges of the valve handle plates 19 and 20 is a thumb lever 29, the inner end of which is forked as at 30 for engaging within notches 31—31 and the sides of the pins 25 as clearly disclosed in Figure 7. Threaded through an opening in the thumb lever 29 in back of its pivotal connection to the plates 19 and 20 is a thumb screw 32, that when screwed downwardly will engage the upper edges of the plates 19 and 20, for preventing the pivotal action of the same in a direction to cause the raising of the plunger carrying pin 25 with the result that when the tit 26 of the plunger is arranged within one of the openings of the segment 10, the handle cannot be accidentally turned from a set position.

The particular operation, as well as the detailed features of construction will be readily apparent to those skilled in the art, and will furthermore appreciate that I have considerably improved upon the device shown and described in the previously mentioned application for patent.

Having thus described my invention, what I claim as new is:

1. In combination with a gas stove valve, wherein the latter includes a body, and a valve stem handle, a clamp rigidly attached to the valve stem handle, a vertically movable pin carried by the clamp, a unit detachably rigidly associated with the valve body and including a horizontally disposed segment provided with a series of spaced openings throughout the length thereof for receiving the lower end of the pin whereby the valve may be maintained locked in any predetermined position, a manually operable member pivotally arranged on the clamp, and operatively connected at one end with the upper end of the pin for facilitating the raising of the pin out of engagement with the openings in the segmental plate to permit the turning of the handle.

2. In combination with a gas stove valve, wherein the latter includes a body, and a valve stem handle, a clamp rigidly attached to the valve stem handle, a vertically movable pin carried by the clamp, a unit detachably rigidly associated with the valve body and including a horizontally disposed segment provided with a series of spaced openings throughout the length thereof for

receiving the lower end of the pin whereby the valve may be maintained locked in any predetermined position, a manually operable member pivotally arranged on the clamp, and operatively connected at one end with the upper end of the pin for facilitating the raising of the pin out of engagement with the openings in the segmental plate to permit the turning of the handle, and means for locking the pivoted member against swinging movement.

3. In a locking device for a gas stove valve, wherein the latter includes a body, and a valve stem handle, the inner end of which is provided with a head, a pair of removable clamping plates disposed upon the opposite sides of the valve body, a segment upon the upper end of one of the plates and disposed horizontally, said segment being provided with a series of spaced openings, a removable unit attached to the inner headed end of the valve stem handle, a sleeve carried by the unit, a pin guide disposed within the sleeve, a pin movable vertically in the guide and adapted for engagement at its lower end within any one of the openings formed in the aforementioned segment, spring means between the pin and the guide for normally holding the pin in locking engagement with the segment, and hand controlled means associated with the pin and said handle unit for facilitating the raising of the pin so that said handle may be turned.

4. In a locking device for gas stove valves, wherein the latter includes a body, and a valve stem handle, the inner end of which is provided with a head, a pair of removable clamping plates disposed upon the opposite sides of the valve body, a segment upon the upper end of one of the plates and disposed horizontally, said segment being provided with a series of spaced openings, a removable unit attached to the inner headed end of the valve stem handle, a sleeve carried by the unit, a pin guide disposed within the sleeve, a pin movable vertically in the guide and adapted for engagement at its lower end within any one of the openings formed in the aforementioned segment, spring means between the pin and the guide for normally holding the pin in locking engagement with the segment, hand controlled means associated with the pin and said handle unit for facilitating the raising of the pin so that said handle may be turned, an additional means whereby the last mentioned means may be locked against movement.

5. In a locking device for gas stove valves, wherein the latter includes a body, and a valve stem handle, a unit constructed for detachable association with the body of the valve, a segment carried by the upper portion of the unit and disposed horizontally, said segment being provided with a series of spaced openings, a unit associated with the

inner end of the valve stem handle, a pin guide carried by said unit, a pin vertically movable within the guide and adapted for engagement at its lower end within any one of the openings formed in the segment, spring means for normally forcing the pin into one of the openings of the segment, a thumb lever pivoted intermediate its ends to the top of the handle attaching unit, and a connection between one end of the thumb lever and said pin whereby the pin may be raised so as to release the valve in order that the handle may be turned to open or closed position.

6. In a locking device for gas stove valves wherein the latter includes a body, and a valve stem handle, a pair of clamping plates constructed for engagement upon opposite sides of the valve body, means at the upper and lower ends for the plates for securing the same rigidly to the valve body, a segment

upon the upper end of one of the clamping plates and disposed horizontally, said segment being provided with a series of spaced openings, a clamping unit arranged on the inner end of the valve stem handle, a sleeve carried by the unit, a pin guide arranged in the sleeve, a pin vertically movable in said guide, means at the lower end of the pin for engagement within any one of the openings formed in the segment, a thumb lever pivoted intermediate its ends to the valve handle clamping unit, and connected at its inner end to the upper end of the pin for facilitating the raising of the pin from the segment, and means within the guide and associated with the pin for forcing the same to normally engage in one of the openings in the segment.

In testimony whereof I affix my signature.

EMILE N. TROTTIER.
